UNITED STATES PATENT OFFICE.

OSCAR RAYMOND ROSE, OF CHICAGO HEIGHTS, ILLINOIS.

DESIGN FOR A BREASTPIN OR BADGE.

58,450.

Specification for Design.

Patented July 19, 1921.

Application filed December 20, 1917. Serial No. 208,186. Term of patent $3\frac{1}{2}$ years.

To all whom it may concern:

Be it known that I, OSCAR RAYMOND ROSE, a citizen of the United States, residing at Chicago Heights, in the county of Cook, State of Illinois, have invented a new, original, and ornamental Design for Breastpins or Badges, of which the following is a specification, reference being had to the accompanying drawing, forming part thereof.

Figure 1 is a perspective view of a pin or badge showing my new design.

Fig. 2 is a plan view thereof.

Fig. 3 is a vertical sectional view of the pin or badge shown in Fig. 1.

I claim:

The ornamental design for a breastpin or badge as shown.

Applicant's name is signed to this application in the presence of two witnesses.

OSCAR RAYMOND ROSE.

Witnesses:

HARRISON K. EVAN,

HENRY SCHULZE.
